UNITED STATES PATENT OFFICE

ELLA E. HERRMANN, OF CANNELTON, INDIANA, ASSIGNOR TO THE LEHMAN COMPANY OF AMERICA, OF CANNELTON, INDIANA, A CORPORATION OF INDIANA

DESK AND BLACKBOARD ARRANGEMENT

Application filed January 27, 1932. Serial No. 589,191.

The present invention relates to improvements in furniture, and has particular reference to a combined desk and blackboard arrangement.

5 Heretofore several types of combined desk and blackboard arrangements have been known, but these arrangements have been unduly complex and conducive to damage to the desk structure.

10 A primary object of the present invention is to provide a novel arrangement of a desk of the "roller-top" type and a blackboard, whereby, when in use the blackboard is positioned at a convenient angle at the front of the desk.

15 An additional object is to provide means whereby the blackboard is prevented from damaging the table portion of the desk, which is ordinarily polished and therefore subject to damage by scratching and the like.

20 Still another object is to provide a desirable arrangement for positioning and supporting the blackboard on the desk when the blackboard is not in use.

25 These and other objects will be apparent from a consideration of the following description of a preferred modification of my invention and by reference to the accompanying drawing, in which

30 Fig. 1 is a perspective view of a child's or miniature roller-top desk, showing the top rolled upwardly;

35 Fig. 2 is a similar view showing a blackboard positioned at the front of the desk in accordance with my invention;

Fig. 3 is a perspective view showing a rack structure mounted on the back of the desk and having a blackboard positioned therein;

40 Fig. 4 is a detailed view, partly in section, taken along line 4—4 of Fig. 2; and

Fig. 5 is a detailed view, partly in section, taken along line 5—5 of Fig. 3.

In the drawing, 10 represents a roller-top desk of reduced size and adapted to be used by children. The upwardly extending sides 11 of the desk are provided with arcuate channels 12 which carry the ends of roller-top 13 in the usual manner. To close the desk, the top 13 is rolled down into contact with the horizontal table portion 14. A cap-

board 15 is mounted across the sides 11 at the upper portion thereof.

To each of the sides 11 is attached a peg 16. These pegs are positioned back of channels 12, so that the top of the desk may be closed, 55 and above the table portion 14.

The frame of blackboard 17 is provided with a recess 18 in each of its side portions. These recesses communicate with the bottom of the frame and extend up the side a relatively short distance, as shown in Fig. 4, and form a shoulder or stop 19.

When it is desired to use the blackboard, it is positioned so that the slots 18 receive inwardly extending pegs 16. Shoulders 19 engage the pegs 16 to support the blackboard against further downward movement and against backward or forward movement. By positioning pegs 16 a short distance above the table portion 14 and the shoulders 19 adjacent 60 the bottom of the blackboard frame, it is possible to space the blackboard from the table portion 14. The finish of the table portion is thereby protected against being marred by contact with the blackboard. 70

The pegs 16 thus support the blackboard and hold the lower portion thereof steady. The upper portion of the blackboard pivots about the pegs 16 and rests against the edge 80 of top 13 or against the cap-board 15, depending upon the position of the top. Ordinarily, it will be found preferable to rest the blackboard against the cap-board, but a more vertical angle may be secured by moving the top 85 into forward position.

When the blackboard is in operative position, it is possible to gain access to the interior of the desk by merely rotating the blackboard about the pegs 16. Lifting or otherwise removing the blackboard from the pegs is thereby made unnecessary.

To the back of the desk are mounted two vertical L-shaped racks 20 which receive the blackboard 17. The bottom of each rack 95 is provided with a stop portion 21 which limits the downward movement of the blackboard. The lower portion of the blackboard is inserted in the opening formed by the complementary racks 20 and is allowed to slide 100

downwardly into engagement with the stops 21.

With a blackboard holder of this type positioned on the rear of the desk, it is possible 5 to place the desk in contact with a wall, as it is customary to position desks, and to insert or withdraw the blackboard without moving the desk from its position against the wall. In fact, I have found that the wall forms a 10 guide for the blackboard which facilitates insertion of the board into the racks. Also, the base of the L-shaped racks which extend parallel to the back of the desk spaces the blackboard from the wall, whereby the wall paper 15 is not damaged by insertion or withdrawal of the blackboard.

Various modifications of my invention will occur to one skilled in the art and such as come within the spirit of my invention are 20 intended to be included in the appended claims.

I claim:

1. In combination, a roller-top desk having 25 a horizontal table portion, arcuate side portions extending upwardly therefrom, said sides being provided with a channel adjacent the periphery thereof, a roller-top traveling in said channels, a cap-board joining said sides at their upper portion, and pegs extending inwardly from said sides adjacent the front of the desk and spaced from the table portion thereof, with a blackboard having slots for engaging said pegs to support said blackboard.

35 2. In combination, a roller-top desk having a horizontal table portion, vertical sides extending upwardly from said table portion, and being provided with top-receiving channels adjacent their peripheral portions, a cap- 40 board joining said sides at their upper portion and adjacent the rear of the desk, a roller-top mounted in said channels, a peg extending inwardly from each of said sides and being positioned back of the top-receiving 45 channels in said sides and a short distance above the table portion and a blackboard provided with recesses in its lower portion for engaging said pegs.

In testimony whereof I have hereunto sub- 50 scribed my name.

ELLA E. HERRMANN.
